UNITED STATES PATENT OFFICE.

HYMAN ELI GOLDBERG, OF CHICAGO, ILLINOIS, ASSIGNOR TO GOLDBERG CALCULATING MACHINE COMPANY, A CORPORATION OF ILLINOIS.

CALCULATING-MACHINE.

No. 893,722.

Specification of Letters Patent.

Patented July 21, 1908.

Application filed January 8, 1906. Serial No. 295,132.

To all whom it may concern:

Be it known that I, HYMAN ELI GOLDBERG, a citizen of the United States, residing at Chicago, in the county of Cook and State of Illinois, have invented a certain new and useful Improvement in Calculating-Machines, of which the following is a specification.

My invention relates to calculating machines, by which is meant to include calculating attachments to typewriters, and as here illustrated, the invention is embodied in a typewriter attachment.

The objects of the invention are to provide improved full stroke mechanism and restoring mechanism, the purpose of the first being to prevent the rise of a key until it has completed enough of its downward stroke to register or set up the proper digit. The purpose of the restoring mechanism is to afford means whereby after the operator has discovered the fact that a key has been insufficiently depressed he may positively force or restore all of the parts, including the figure wheels, to original position. The keys themselves are, as usual, spring-urged to return the parts to normal position, but the key-springs may or may not be strong enough to do so, and with my restoring mechanism, which among other functions, supplements the action of the key-springs, the parts may be actually forced to original position. Moreover, my restoring mechanism is operative upon all of the keys so that if more than one is retained part way down as a result of improper depression, all will be simultaneously returned to original position.

I attain my objects by the mechanisms illustrated in the accompanying drawings in which;

Figure 1 is a general front elevation of a typewriter and attachment embodying my invention. Fig. 2 is a transverse sectional elevation thereof taken on line 2—2. Fig. 1. Fig. 3 is a plan view showing the relationship of the digit pieces, toothed sectors, locking shaft, digit shaft, and restoring mechanism. Fig. 4 is a face view of a digit piece, and locking pinion. Fig. 5 is a sectional view taken on line 5—5. Fig. 4. Fig. 6 is a sectional view similar to Fig. 5 but shows the locking pinion rotated one eighth of a revolution from the position shown in Fig. 5. Figs. 4, 5, and 6 serve to illustrate the co-operation of the digit pieces with the locking pinions.

Fig. 7 is a fragmentary plan view of the restoring lever and adjacent parts. Fig. 8 is an elevation of the parts shown in Fig. 7. Figs. 9, 10, and 11 are sectional elevations of the restoring mechanism taken respectively on the lines 9—9, 10—10, and 11—11, Fig. 7. Fig. 12 is a front view of a toothed driving sector together with the shaft on which it is mounted. This figure also illustrates the spacing collar and the position of the restoring tooth of said shaft. Fig. 13 is a side view partly in section of the parts shown in Fig. 12. The section is taken on line 13—13. Fig. 14 is a fragmentary view of the shaft which supports the toothed driving sector. This shaft carries the restoring teeth for restoring the driving sectors to original position and for convenience may be referred to as the "restoring" shaft. Fig. 15 is a fragmentary detail view of the gearing for transmitting rotation from the digit shaft to the valuating shaft. Figs. 16 and 17 are plan and side views respectively showing a suitable form of mounting for the keys.

Similar numerals refer to similar parts throughout the several views.

The general construction of the machine here shown is also shown and described in Patent No. 782,554 issued to me February 14, 1905; and the parts which embody the present invention are more especially illustrated in Figs. 7 to 14 inclusive in the accompanying drawings.

The framework 1 of the typewriter supports the laterally shiftable typewriter carriage 2 and the typewriter keys 3. Each of the number keys of the typewriter is connected to a driving sector 4 by means of a link 5 or otherwise in such manner that the depression of the key will cause the movement of the sector and conversely the movement of the sector is capable of producing a movement of the key. As usual in machines of this class the keys are spring influenced to rise to normal position. Any suitable construction may be employed and for the purpose of illustration an example is shown in Figs. 16 and 17. In the form selected the keys are fulcrumed upon a lug 1^a and are held in contact therewith by means of springs 1^b. A universal bar 50 extends beneath all of the keys and said bar is urged upward by means of rods 51 connected to the frame 52. Said frame is urged in upward direction by

means of a spring 53 which engages a stationary portion 54 of the machine frame 1.

The driving sectors 4 are mounted so as to rotate independently upon shaft 6 and are provided with gear teeth adapted to mesh with the gear teeth 7 of the digit pieces 8. Said sectors are prevented from lateral movement on shaft 6 by means of the spacing collars 6^a or other suitable means.

- 10 There is a digit piece for each of said driving sectors, and they are mounted upon shaft 9 in such manner as to be both independently rotatable and independently shiftable thereon. Shafts 6 and 9 are supported by suitable portions 10, 11, 12 and 13 of the stationary framework.

The lateral shifting of the digit pieces upon their shaft is caused by pin 14^a which are rigidly fixed in the stationary frame portion 20 14 and adapted to act upon the inshifting cams 15 and outshifting cams 16 on the digit pieces as best illustrated in Figs. 2, 3 and 4. The parts are so constructed that when a driving sector is rotated about shaft 6 as an axis it causes the rotation of the corresponding digit piece about shaft 9 as an axis and also causes the lateral shifting of the digit piece lengthwise of shaft 9. The faces of gears 7 are wide enough to remain in mesh 25 with driving sectors 4 in both shifted positions of the digit pieces. Said digit pieces perform two functions, one of which is to rotate the digit pinions 17 which are rigidly fastened to or integral with shaft 18, and to 30 rotate the locking pinions 19 and 20 which are rigidly fastened to or integral with locking shaft 21. Said digit pinions 17 are complete spur gears while the locking pinions 19 and 20 each have four teeth corresponding 35 to the alternate teeth of an eight-toothed gear wheel—in other words, are like an eight toothed gear wheel from which the alternate teeth have been cut away; and they are so arranged upon the locking shaft that a 40 tooth on one is opposite to the space between the teeth on the other, so that when they are viewed from the side they have the appearance of forming a complete gear as illustrated in Figs. 5 and 6.

- 45 Shafts 18 and 21 are rotatably mounted in the stationary frame portions 10, 11, 12, and 13 and as their respective pinions are rigid on said shafts the rotation of any one of the pinions causes a corresponding rotation of their respective shafts. The digit pinions are rotated by the toothed digit sectors 22 which are most clearly shown near the bottom of Fig. 2. Said digit sectors are incomplete toothed gear wheels, the number 50 of teeth whereof depends upon the value of the figure key to which it is connected. In the present construction, which is the one preferred, the "1" digit sector has one tooth, the "2" digit sector has two teeth, and so on, 55 and the relation of the parts is such that a

digit sector will be in mesh with its digit pinion during the forward stroke of the digit sector but will be shifted out of mesh after the completion of the forward rotation so that a digit sector will rotate back to original position without rotating the digit pinion. Consequently the digit sectors rotate backward and forward but the digit pinion shaft rotates always in the same direction, and the amount of rotation depends upon the value of the key temporarily in action.

60 It will be noted that a digit piece is positively geared with its digit pinion during its forward motion and that therefore in case of an incomplete motion of a digit piece such digit piece and its digit pinion may both be returned to their original position by restoring the driving sector to original position. Since all of the other parts of the mechanism, 65 including the totalizer wheels (hereafter referred to) are in geared connection with the digit pinion shaft, this restoration of the digit pinion shaft restores all the other parts to their original position. Moreover as the digit 70 pieces are in positive gear-and-link connection with the figure keys, should anything prevent the negative rotation of the digit pinions in the case of an incomplete positive rotation thereof, the connected figure key 75 will be prevented from rising to normal position, thus calling the attention of the operator to the fact that the key has been insufficiently depressed.

The function of the locking shaft and its 80 pinions is to prevent accidental movement of the digit shaft 18; and in the present design the locking of the digit shaft is accomplished through the agency of the locking pawl 23 which is pivotally mounted upon the 85 stationary shaft 24 and bifurcates into two arms 25 and 26 as shown in Fig. 2. The extremity of arm 25 is adapted to enter between the teeth of a detent pinion on digit shaft 18, and although a special pinion might 90 be employed for the purpose, it is preferable to make use of one of the aforesaid digit pinions 17. Pawl 23 is positively operated by a pinion on locking shaft 21 and for convenience, use is made of one of the locking 95 pinions 19 above mentioned. The teeth of said pawl-operating pinion act upon the inner edges of arms 25 and 26, the parts being so arranged that when the pawl-operating pinion is in one position, a tooth will 100 abut the rear edge of arm 25 and hold the same positively in engagement with the teeth of the detent pinion, but when said operating pinion is rotated one eighth of a revolution in either direction the arm 25 will 105 be released, and one of the teeth will act upon the arm 26 to force the same and arm 25 away from the detent pinion. Thus the pawl-operating pinion acts positively upon pawl 23 and the locking shaft will operate 110

said pawl first to lock and then release the digit pinion shaft by being successively rotated 45° at a time, that is to say one eighth of a revolution. These successive partial rotary movements of the locking shaft are accomplished by means of locking disk sectors 27, 28 and 29 formed upon the digit pieces 8 in the manner best shown in Figs. 4, 5 and 6. The locking disk sectors 27 and 28 are circumferentially located some distance apart and are in line with the locking pinion 19, while the sector 29 is in line with the locking pinion 20. Said locking sectors are so distributed that when viewed from the side their ends appear to overlap and the overlapped area corresponds to a gear tooth as indicated in Figs. 5 and 6. The construction and arrangement is such that, by means of the digit piece, the locking shaft 21 is locked just prior to the commencement of its rotation, is then rotated one tooth space just prior to the commencement of rotation of the digit pinion shaft 18, remains locked by said sector 29 during the period of rotation of said digit pinion shaft, and is then rotated one tooth space more immediately after said digit pinion shaft has completed its rotation, and is then again locked. The actions of the disk sectors on the locking pinions occurs only during the positive rotation of the digit pieces, said digit pieces and disk sectors thereon being shifted out of operative position during the return rotation by means of the action of the outshifting cam 16.

As shown in Figs. 2 and 15 one of the pinions on the digit shaft 18 meshes with the gear wheel 30 which thus rotates every time a figure key is struck, its amount of rotation depending upon the key's value. Gear 30 meshes with the pinion 31 on valuating shaft 32 which in turn is geared to the master or setting wheel 33 as shown in Fig. 1. Wheel 33 meshes with the totalizer wheels 34 of the totalizer 35 when the latter is in juxtaposition. The construction and operation of the above described parts or their equivalents is fully set forth in said prior patent No. 782,554; and the form of totalizer shown is described in Patent No. 710,772 issued to me October 50 7, 1902.

Although there may be considerable variation in the design of the parts it is to be noted; first, that the connections from the keys to the totalizer wheels are such that if, 55 after a key has been partly depressed but not sufficiently to register the proper digit, the key be raised to normal position, the totalizer wheels will be returned to original position; second, that when the digit shaft is locked 60 everything is locked, including the keys as well as the totalizer wheels; third, that when the locking shaft is locked in normal position, the digit shaft is locked, so that the entire mechanism may be locked by applying a 65 detent to either the digit shaft or the locking

shaft or both. It will also be borne in mind that said shafts always rotate in the same direction and that the locking shaft must always move before the digit shaft can move. With the above considerations in mind, reference will now be made more especially to Figs. 7 to 14 inclusive which show the details of the full stroke and restoring mechanisms embodying this invention.

Rotatably mounted on shaft 9 is a gear 75 wheel 36 adapted to be manually operated by means of a restoring handle 37. Said gear wheel is urged by a spring 38 to rotate in an anticlockwise direction to return to and maintain its normal position which is the position shown in Figs. 9, 10 and 11. A pinion 39 is rigidly fastened to the restoring shaft 6 and is adapted to mesh with gear 36. Pinion 39 is preferably smaller than gear 36 so as to multiply the rotary movement of handle 37. 80 The cam 40 is also rigidly fastened to shaft 6 so that, as a result, when handle 37 is pulled forward, the cam 40 will rotate in an anticlockwise direction.

Loosely and independently mounted on 90 shaft 9 in line to be acted upon by cam 40 are two pawls 41 and 42 which are adapted to engage the ratchet pinions 43 and 44 respectively on digit shaft 18 and locking shaft 21 respectively. Said pawls are urged by 95 springs 45 and 46 respectively to remain in engagement with their ratchet pinions 43 and 44 and are so designed as to permit their respective pinions to rotate in a positive direction, that is, the direction taken in the 100 normal action of the machine in setting up a digit. But they prevent the negative rotation of said pinions unless released by hand against the force of their springs; and the means for thus releasing said pawls is the 105 cam 40 above mentioned, which is so shaped that when pinion 39 and shaft 6 are in normal position (Figs. 10 and 11) said cam will not interfere with said pawls but when rotated in an anticlockwise direction, as a result of the forward pulling of handle 37, will 110 raise said pawls clear of the teeth of pinions 43 and 44. Said pawls therefore always permit the proper positive rotation of the locking shaft and digit shaft but prevent them 115 from rotating negatively, negative rotation being never necessary in the proper normal operation of the machine. But the preventing of negative rotation of the digit pinion shaft 18 prevents the rise of an insufficiently depressed key and thereby calls the attention of the operator to the mistake. When the attention of the operator has been called to the mistake he may remedy it by pulling the 120 handle 37 forward and thus release both of the pawls 41 and 42 from their ratchet pinions 43 and 44 and permit the connected key to rise and thereby return the parts, including the totalizer wheels, to normal position.

As above stated, the locking of the locking 130

shaft locks the mechanism and therefore pawl 42 which prevents negative rotation of said locking shaft is sufficient to prevent the complete rise of an insufficiently depressed key. But this arresting of the rising key by pawl 42 after incomplete depression does not occur at the lowest point of key depression but only just before the end of the return. This is due to the fact that normally the only movement occurring in the locking shaft is one (for example as in the present design, one eighth of a revolution) occurring just prior to the commencement of the rotation of the digit shaft, and another similar movement just after the completion of rotation of the digit shaft; and it is obvious that in negative operation the normally-first movement of the locking shaft would not occur until near the end of the operation, the locking shaft in the meantime remaining still. Hence by applying the detent to the locking shaft alone the key would be held depressed, but only slightly. But by acting also upon the digit shaft, to arrest it at its furthest acquired position, the key also is held at its lowest acquired point of incomplete depression. And it is to thus arrest said key at its furthest acquired depression that the pawl 41 is provided.

30 As above stated, the operations of pawls 41 and 42 are such that a key which has been only partially depressed will be prevented from rising. Consequently it is true that if the operator has touched a key and subsequently sees that it has risen again to normal position he may be sure that either the depression has been complete or else so insufficient as not to start the operation of registering. It is desirable also that the operator should be able to determine whether the depression was sufficient or not by merely noting whether or not the typewriter carriage has shifted laterally, that is, whether the carriage escapement has operated or not. But in order that the carriage may thus be a positive index, it is necessary that the escapement action should occur within the period or range of activity of the key-retaining devices. If pawl 41 only were employed, this period or range, especially in the "1" key would be very short, and as the typewriters in ordinary commercial use are not constructed with very great accuracy with regard to the exact time of operation of the carriage escapement it becomes very desirable to extend the limits of the period during which the escapement of the carriage may take place and yet come within the operative period of the key-retaining devices. This extending of the limits is herein accomplished by the use of pawl 42 acting upon shaft 21 which, it will be remembered, moves just before and just after the period of rotation of the digit shaft 18. Thus by the use of the two pawls in conjunction, the operative period of the key-retaining de-

70 vices is extended. In other words, pawl 42 is operative upon a key both before and after pawl 41 is operative, and thus the period is extended; but pawl 42 is not operative to retain a key during the interim. The retaining at intermediate points is attended to by pawl 41. It is true, of course, that the actual registering of the digit upon the totalizer is complete as soon as digit shaft 18 has completed its motion. Pawl 42 therefore is still 75 operative as a key retainer after registration is complete.

76 Now as to the restoring mechanism. It may occur that the key springs of the ordinary typewriter are not strong enough to return all of the parts to normal position, and to assist in this I provide a positive acting 80 restoring mechanism the chief parts of which are shown in Figs. 2, 9, 12 and 13. It has already been mentioned that shaft 6 upon 85 which the toothed driving sectors 4 are mounted rotates in an anticlockwise direction for operating pawl 40 when handle 37 is operated. It is also true that said driving sectors are so connected as to rotate in an 90 anticlockwise direction when they and the other parts, including the keys, are returning to normal rest position. I take advantage of this relation by forming shoulders 47 upon the hubs of said driving sectors and fasten 95 teeth or short keys 48 upon shaft 6 in positions to engage said shoulders as best shown in Figs. 12 to 14. The parts are so related that when handle 37 and shaft 6 are in normal rest position the restoring teeth 48 do 100 not interfere with the action of the sectors 4 nor keys 3, but when said handle is operated from normal position said restoring teeth will rotate in an anticlockwise direction far enough to restore any or all of said sectors to 105 normal position.

110 It will be understood that the terms "clockwise" and "anticlockwise" are employed for convenience of description only, and that the essential feature is that the pawls 41 and 42 permit the forward rotation of shafts 18 and 21 and prevent the negative rotation thereof unless released by the positive movement of handle 37, which positive movement of said handle also actually forces any or all of the 115 driving sectors and connected parts back to normal position. It will also be understood that any kind of an arm, projection or shoulder may be employed on shaft 6 to engage any part of or attachment to the driving sectors to return them to normal position; also that the restoring handle 37 might be fastened directly to shaft 6 instead of being geared thereto, with the disadvantage however that the direction of movement would 120 not be so convenient for the operator nor would the necessary movement be effected by so slight a throw of said handle.

125 It is obvious that the full stroke mechanism may exist apart from the restoring mech- 130

anism, but it is of special convenience and advantage that both of them are operated from the same operating handle 37.

Although I have illustrated detaining means for preventing the travel of the carriage and totalizer during the operation of the valuating parts, I do not here make claim to the same as it is claimed generally in a copending application filed May 28, 1904, Serial No. 210,158, and specifically in another copending application filed January 17, 1906, Serial No. 296,491.

What I claim as new and desire to secure by Letters Patent, is;

15 1. In a calculating machine the combination of operating keys which tend to return to normal position when depressed, means for retaining a key in depressed position if not sufficiently depressed; a rotatable cam operative upon said retaining means for releasing said keys; and hand operated means for rotating said cam.

20 2. In a calculating machine the combination of operating keys which tend to return to normal position when depressed, means for retaining a key in depressed position if not sufficiently depressed; a rotatable cam operative upon said retaining means for releasing said keys, gears for multiplying the rotary movement of said cam; and a handle for operating said gears, said handle being spring urged to remain in normal position to hold said cam in non active position.

25 3. In a calculating machine, the combination of a totalizer, means for actuating the same, and full stroke mechanism; said actuating means including self-returning depressible figure keys and two shafts operated by said keys, and normally rotating always 30 in the same direction, one of said shafts rotating an equal amount for every key and the other rotating an amount depending upon the value of the key struck; and said full stroke mechanism including means operative upon said shafts prior to the completion 35 of their positive rotation for automatically preventing negative rotation thereof, and manually operated means for releasing said preventing means to render the same inoperative upon said shafts.

40 4. In a calculating machine, the combination with a totalizer, of keys for operating the totalizer, said keys tending to return to normal position when depressed and being adapted to restore the totalizer to previous 45 condition upon their return in case of insufficient depression, means for retaining a key in depressed position if not sufficiently depressed, and hand operated means for releasing said keys.

45 5. In a calculating machine, the combination with a totalizer, of keys for operating the totalizer, said keys tending to return to normal position when depressed, and being adapted to restore the totalizer to previous

condition upon their return in case of insufficient depression, a ratchet device for retaining a key in depressed position if not sufficiently depressed, said ratchet device including a toothed member and a pawl adapted to act thereon, one of said parts of the ratchet device being non yieldingly connected to the key whereby the movement of one controls the movement of the other, and means for releasing said key at any point of its depression. 75

6. In a calculating machine, a totalizer, depressible figure keys, and valuating mechanism operated by said keys and adapted to actuate said totalizer, said valuating mechanism including a set of reciprocating parts one connected to each figure key and adapted to reciprocate forward and back with the movement of the respective keys; in combination with hand operated means for positively restoring a key to normal position. 85

7. In a calculating machine a totalizer, depressible figure keys, and valuating mechanism operated by said keys and adapted to actuate said totalizer, said valuating mechanism including a set of reciprocating parts one connected to each figure key and adapted to reciprocate forward and back with the movement of the respective keys; in combination with a restoring member adapted to influence all of said reciprocating parts to 95 positively return them to normal position and means for operating said restoring member.

8. In a calculating machine a totalizer, depressible figure keys, and valuating mechanism operated by said keys and adapted to actuate said totalizer, said valuating mechanism including a set of reciprocating parts one connected to each figure key and adapted to reciprocate forward and back with the movement of the respective keys; in combination with a restoring shaft extending across all of said reciprocating parts and adapted to contact any and all of them for positively restoring them and the keys to 110 normal position; and means for operating said restoring shaft.

9. In a calculating machine a totalizer, depressible figure keys, and valuating mechanism operated by said keys and adapted to 115 actuate said totalizer, said valuating mechanism including a set of reciprocating parts one connected to each figure key and adapted to reciprocate forward and back with the movement of the respective keys; in combination with a restoring shaft extending across all of said reciprocating parts and adapted to contact any and all of them for restoring them and the keys to normal position; and a handle connected to said restoring shaft for manually operating the same. 125

10. In a key operated calculating machine, the combination of self returning depressible keys, means for retaining a key in partially depressed position, means for releasing said

- retaining means, means for positively restoring a key to original position, and means for simultaneously operating said releasing means and said restoring means.
- 5 11. In combination, a totalizer, means including depressible figure keys for actuating said totalizer, means for retaining a key in partially depressed position, a hand operated member, means operated by said hand operated member for releasing said retaining means, and other means operated by the same hand operated member for positively restoring the key to normal position after its release.
- 15 12. In combination, a totalizer, means for actuating the same, full stroke mechanism and restoring mechanism; said actuating means including a rotatable member adapted to be connected to said totalizer, depressible figure keys and valuating connections between said keys and said rotatable member; and said full stroke mechanism including means for retaining a key in partially depressed position and hand operated means for releasing said retaining means; and said restoring mechanism including hand operated means for positively restoring the key to original position, said releasing and restoring mechanisms having one part in common whereby they are operable simultaneously.
13. In combination, a totalizer, means for actuating the same, full stroke mechanism and restoring mechanism; said actuating means including a rotatable member adapted to be connected to said totalizer, depressible figure keys and valuating connections between said keys and said rotatable member; and said full stroke mechanism including means for retaining a key in partially depressed position and hand operated means for releasing said retaining means; and said restoring mechanism including hand operated means for positively restoring the key to original position, said releasing and restoring mechanisms having one part in common whereby they are operable simultaneously.
14. In combination, a totalizer, means for actuating the same and full stroke mechanism; said actuating means including a rotatable member, self returning depressible figure keys, digit pieces one connected to each figure key and adapted to rotate said rotatable member an amount depending upon the value of the key struck, a locking member adapted to lock and release said rotatable member, said digit pieces being adapted to move said locking member to release said rotatable member just prior to the rotation thereof and again just subsequently to again lock it; and said full stroke mechanism including two ratchet and pawl devices one operative upon said rotatable member and the other on said locking member for preventing the rise of a partially depressed key; and means for releasing both preventing means.
15. A totalizer and means for actuating the same, said actuating means including a digit member moving different amounts depending upon the value of the digit to be registered, and reciprocating number keys all operative upon said digit member; and a second member adapted to move prior to the movement of said digit member for releasing the same; in combination with means operative upon second member for retaining a number key in partially depressed position.
16. A totalizer and means for actuating the same, said actuating means including a digit member moving different amounts depending upon the value of the digit to be registered, and reciprocating number keys all operative upon said digit member; and a second member adapted to move subsequently to the movement of said digit member for locking the same; in combination with means operative upon said second member for retaining a number key in partially depressed position.
17. A totalizer and means for actuating the same, said actuating means including a digit member moving different amounts depending upon the value of the digit to be registered, and reciprocating number keys all operative upon said digit member; and a locking member adapted to move prior to and also subsequently to the movement of said digit member for releasing and locking the same; in combination with means operative upon said locking member for retaining a number key in partially depressed position.
18. A totalizer, and means for actuating the same, said actuating means including a digit member rotating different amounts depending upon the digit to be registered, and reciprocating number keys all operative upon said digit member; in combination with a locking member adapted to move prior to the movement of said digit member for releasing the same, means operative upon said locking member for retaining a key in partially depressed position; and hand operated means for releasing said retaining means.
19. A totalizer, and means for actuating the same, said actuating means including a digit member rotating different amounts depending upon the digit to be registered, and reciprocating number keys all operative upon said digit member; in combination with a locking member adapted to move prior to the movement of said digit member for releasing the same and subsequently to the movement of said digit member for locking the same; means operative upon said locking member for retaining a key in partially depressed position; and hand operated means for releasing said retaining means.

20. A totalizer and means for actuating the same, said actuating means including a digit shaft rotating always in the same direction different amounts depending upon the 5 value of the digit to be registered, and de-pressible figure keys all operative upon said digit shaft for rotating the same; a locking digit shaft, means operated by said locking shaft for locking said digit shaft, and means oper- 10 ated by said keys for rotating said locking shaft prior to the movement of said digit shaft for releasing said digit shaft; in combination with means operative upon said locking shaft for retaining a key in partially 15 depressed position and means for releasing said retaining means.

21. A totalizer and means for actuating the same, said actuating means including a digit shaft rotating always in the same direc- 20 tion different amounts depending upon the

value of the digit to be registered, and de-pressible figure keys all operative upon said digit shaft for rotating the same; a locking digit shaft, means operated by said locking shaft for locking said digit shaft, and means oper- 25 ated by said keys for rotating said locking shaft prior to the movement of said digit shaft for releasing said digit shaft; in combination with means operative upon said locking shaft for retaining a key in partially 30 depressed position and means for releasing said retaining means.

In witness whereof, I have hereunto sub- 35 scribed my name in the presence of two wit-nesses.

HYMAN ELI GOLDBERG.
